Term of patent 14 years

Int. Cl. D14—02

U.S. Cl. D26—5

The single figure of the drawing is a perspective view of an instrument housing embodying my new design.

The side of the housing opposite the one illustrated is identical to the illustrated side, and the back and bottom of the housing are substantially flat and plain in appearance.

I claim:

The ornamental design for an instrument housing or similar article, substantially as shown and described.
